(57) **CLAIM**

The ornamental design for a controller for biological information monitoring device, as shown and described.

DESCRIPTION

FIG. 1 is a front, top and right-side perspective view of a controller for biological information monitoring device showing my new design;

FIG. 2 is a front elevational view thereof;

FIG. 3 is rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the controller for biological information monitoring device that form no part of the claimed design.
